UNITED STATES PATENT OFFICE.

FRED L. MACKENZIE, OF BEVERLY, AND GEORGE GODDU, OF WINCHESTER, MASSACHUSETTS, ASSIGNORS TO UNITED SHOE MACHINERY CORPORATION, OF PATERSON, NEW JERSEY, A CORPORATION OF NEW JERSEY.

WORK-GUIDE.

1,375,796.

Specification of Letters Patent. Patented Apr. 26, 1921.

Application filed July 3, 1918. Serial No. 243,139.

To all whom it may concern:

Be it known that we, FRED L. MACKENZIE and GEORGE GODDU, citizens of the United States, residing at Beverly, in the county of 5 Essex, and Winchester, in the county of Middlesex, respectively, and State of Massachusetts, have invented certain Improvements in Work-Guides, of which the following description, in connection with the accompanying drawings, is a specification, 10 like reference characters on the drawings indicating like parts in the several figures.

This invention relates to guiding devices for machines comprising mechanism for operating on shoe stock and has special reference to devices for guiding a strip or strips of shoe stock into position for operation thereon by said operating mechanism.

It has heretofore been proposed to interpose between the welt and the upper and insole of a welt shoe a filling strip of compressible elastic, and impervious material, such as rubber, which will preclude the seeping of moisture between the welt and the upper and insole or through the perforations made by the welt attaching means, thus making the shoe substantially waterproof. Nailed welt shoes, that is, shoes characterized by the attachment of the welt to the upper and insole by metallic fastenings spaced from each other along the margin of the shoe, may be made substantially waterproof by the interposition of a strip of rubber or like material between the welt and the upper and insole so as to be compressed therebetween when the parts are secured together by the fastenings and thus preclude seeping of moisture between the welt and the upper and insole intermediate of the spaced fastenings or through the perforations of the welt and upper and insole in which the fastenings are inserted. The filling strip is preferably formed with a beaded edge which when the welt and filling strip are laid on the shoe overhangs the margin of the upper and insole adjacent thereto and lies in the angle formed by the welt and upper.

An object of the invention is to facilitate the manufacture of shoes of the type above set forth by the provision of devices for effectively controlling a welt strip and a filling strip and guiding them in superposed relation to the point of operation on the

strips. To this end, the guiding devices are formed to accommodate the bead of the filling strip and by said bead to control the filling strip in its relation to the welt and operating means. The illustrated embodiment of the invention is particularly intended for use in guiding a welt and a beaded filling strip into position for attachment to a shoe by metallic fastenings and is provided with a guiding passage which receives the welt and the filling strip in contact with each other and which is notched in its bottom wall to accommodate the bead on the filling strip and to present surfaces for guiding engagement with the beaded edge of the filling strip.

Although the use of the invention now particularly contemplated is in the attachment to an upper and an insole of a welt and a compressible and waterproof filling strip interposed between the welt and the upper and the insole, it is recognized that the invention as a whole and certain features thereof may have other applications. In one of such aspects, an important feature of the invention resides in the provision of means for guiding a plurality of strips providing a guiding surface arranged for guiding engagement with a side of one of said strips and a member arranged for engagement with the opposite side of said first-mentioned strip and formed to present a guiding surface for engagement with an edge of another of said strips thus effectively controlling said strips and accurately positioning them relatively to each other.

In the illustrated construction, the guiding devices are associated with the guard plate of a fastening inserting machine, the guard plate being provided on one of its sides and rearwardly of the point of insertion of the fastenings with a guiding passage which receives the welt superposed on the filling strip. A second plate secured to the lower surface of the guard plate and hereinafter for convenience sometimes denominated the "guide plate" is formed to present a guiding surface arranged for engagement with the edge of the welt adjacent to the point of insertion of the fastenings and carries a gage roll which operates to position the shoe relatively to the fastening inserting mechanism. Pivoted upon the guide

plate is a finger the end of which is interposed between the end of said plate and the gage roll and is constricted and arranged to underlie a portion of the welt substantially 5 at the point of fastening insertion and to present a guiding surface for engagement with the beaded edge of the filling strip. The pivotal mounting of the finger on the guide plate permits movement of the finger 10 between the lower surface of the end of the plate and the upper surface of the gage roll, the finger being normally pressed against the lower surface of the welt by a spring tending normally to move the end of the 15 finger upwardly toward the lower guiding surface of the guard plate which engages the upper side of the welt. As before indicated, the guiding passage of the guard plate is formed with a notch in its lower wall to 20 receive the bead on the filling strip, and this notch is of greater extent than the bead to permit the bead to be positioned at varying distances from the inner edge of the welt to the end that filling strips of different widths 25 may be accommodated, and, in order that filling strips of different widths may be positively guided into proper relation with the shoe, the aforementioned finger is mounted for endwise adjustment on the guide plate. 30 Other objects and features of the invention will appear as the description proceeds and will be pointed out in the appended claims.

In the drawings,

35 Figure 1 is a view illustrating conventionally a portion of the head of a fastening inserting machine having the invention applied thereto.

Fig. 2 is a cross section of the guard plate 40 and the associated welt and filling strip guiding devices taken substantially through the point of fastening insertion.

Fig. 3 is a top plan view of the guide plate detached from the guard plate.

45 Fig. 4 illustrates a block to which the filling strip guiding finger is pivoted and by which said finger is adjustably mounted relatively to the guard plate, and

Fig. 5 is a view in detail of the finger 50 which guides the beaded edge of the filling strip underlies a portion of the welt.

The fastening inserting machine to which the invention is applied by way of example may be of the type disclosed in the co-pending application of Fred L. Mackenzie, Serial 55 No. 137,152, filed December 15, 1916, comprising the frame 2 which carries a swinging head 4 upon which is mounted the fastening inserting instrumentalities comprising a 60 driver (not shown) and an awl 6. Carried by the main frame 2 is a guard plate 8 which is formed to provide a lower guiding surface 10 (see Fig. 2) leading to and lying at each side of the point of insertion of the fastenings. The shoe to which the welt A and fill-

ing strip B are attached comprises the insole C and upper D and is supported on a horn 11.

The guiding devices for the welt A and filling strip B comprise a bracket 12 adjustably joined to one side of the guard plate 8 by screw and slot connections 14 and formed at its outer end in alignment with the point of insertion of the fastenings with a guiding passage having an upper surface 16 for engagement with the upper side of the welt A, a surface 18 for engagement with the inner edges of both the welt A and the filling strip B, a surface 20 for engagement with the outer or projecting edge of the welt, and a lower wall 22 provided with a notch 24 to receive the bead E on the filling strip and presenting surfaces for guiding engagement with the bead of the filling strip to control the filling strip relatively to the welt and the fastening inserting mechanism and with the side of the strip from which the bead projects. The notch further presents a surface 26 arranged for engagement with the outer edge of the filling strip in substantially parallel relation with the surface 20 which engages the outer edge of the welt. The shape and arrangement of the lower wall 22 with its notch 24 permits the bead of the filling strip to pass through the guiding passage 95 without disturbing the proper guiding relation of the sides and opposite edge of the strip and their respective guiding surfaces. The surface 20 is presented by a part 28 adjustably connected to the bracket 12 by the 100 screw and slot connection 29 whereby the guiding surface 20 is made adjustable relatively to the bracket 12 to adapt it to welts of varying widths. A guide member 30 (see Fig. 2) extends laterally from the forward end of the bracket 12 and presents a guiding surface 31 aligned with the guiding surface 18 and extending to a point adjacent to the point of fastening insertion. By reference to the drawing, it will be seen that the guiding passage in the bracket 12 is formed to receive and guide the welt A and filling strip B in contact with each other and to arrange the welt A and filling strip B transversely in substantially straight lines 115 and in substantially parallel planes. A welt guide of the general type of that thus far described and comprising a bracket formed with a guiding passage to receive a welt and having a part formed to present a guiding 120 surface for the outer edge of the welt which is adjustable relatively to the guiding passage of the bracket is disclosed in the co-pending application of George Goddu, Serial No. 97,015, filed May 12, 1916, on 125 which Patent No. 1,282,809 was granted Oct. 29, 1918.

The guiding passage of the bracket which is spaced from the point of insertion of the fastenings cannot be relied upon invariably 130

Having described the invention, what we claim as new and desire to secure by Letters Patent of the United States is:

1. In a machine of the class described, means for operating on a welt and a filling strip having a bead projecting from its side, and means for guiding the welt and filling strip and presenting them to the operating means in superposed relation constructed to 10 control by said bead the relation of the filling strip to the welt and operating means.
2. In a machine of the class described, means for attaching a welt and a filling strip having a bead projecting from its side to a shoe and means for guiding the welt and filling strip and presenting them to said attaching means in superposed relation having surfaces for guiding engagement with said bead and with the side of the filling strip 20 from which the bead projects.
3. In a machine for attaching a welt and a filling strip having a bead projecting from its side to a shoe, fastening inserting means, and means for guiding the welt and filling 25 strip and presenting them to the fastening inserting means with the welt superposed on the filling strip comprising a member formed with a guiding passage constructed to receive and guide said welt and filling strip in contact with each other and to arrange them transversely in substantially 30 parallel planes and formed with a notch in its bottom wall to receive the bead of the filling strip.
4. In a machine of the class described, means for attaching a plurality of strips of shoe stock of varying widths to a shoe, and means for guiding the strips and presenting them to said attaching means in superposed 35 relation comprising a member having a guiding passage constructed to receive and guide the strips in contact with each other and to arrange the strips transversely in substantially parallel planes and comprising 40 guiding surfaces spaced from each other and arranged in substantially parallel relation and operating to guide the strips independently of each other by engagement with adjacent spaced edges of the strips.
5. In a machine of the class described, a guide formed to receive and guide a plurality of strips of shoe stock in contact with each other and presenting a surface for engagement with the side of one of said strips, 50 and a member arranged for engagement with the opposite side of said strip and presenting a surface for guiding engagement with the edge of another of said strips.
6. In a machine of the class described, a 55 guide formed to receive and guide a plurality of strips of shoe stock in contact with each other and presenting a surface for engagement with the side of one of said strips, a member arranged for engagement with the opposite side of said strip and presenting a 60 surface for guiding engagement with the edge of another of said strips.
7. In a machine of the class described, means for attaching a plurality of strips of shoe stock of varying widths to a shoe, and means for guiding said strips in contacting relation and presenting them to said attaching means in superposed relation comprising 65 mechanism having surfaces to guide one of said strips and a member having a surface arranged to support said strip in operative relation to said guiding surfaces, said member being arranged also to guide another of said strips by engagement with its edge.
8. In a machine of the class described, means for attaching a plurality of strips of shoe stock of varying widths to a shoe, and means for guiding said strips and presenting them to said attaching means in superposed 70 relation comprising a member formed to present a guiding passage arranged rearwardly of the point of attachment of the strips to the shoe and constructed to receive and guide said strips and a member underlying one of said strips and acting to support said strip substantially at the point of attachment of the strips to the shoe and engaging the edge of another of said strips to 75 guide the last mentioned strip substantially at the point of attachment of the strips to the shoe.
9. In a machine of the class described, a guide formed to present a guiding passage to receive and guide a plurality of strips of shoe stock of varying widths and having a surface for engagement with an edge of the wider of said strips and a second surface spaced from the first-mentioned surface for engagement with an edge of a narrower one of said strips to position said last-mentioned strip in proper relation to the first-mentioned strip, said guide also comprising a member underlying a portion of the wider strip and presenting a guiding surface in 80 substantial alignment with the second-mentioned surface of the guiding passage for engagement with the edge of the narrower strip.
10. In a machine of the class described, means for attaching a filling strip having a bead projecting from its side adjacent to one of its edges and a welt to a shoe and means for guiding the filling strip and welt to said attaching means with the welt superposed on the filling strip comprising a member organized for guiding engagement therewith rearwardly of the point of attachment of the filling strip and welt to the shoe and constructed to receive the bead of 85

to locate the welt and filling strip accurately at the point of fastening insertion. Additional means for guiding the welt and filling strip which will positively assure the accurate positioning of the welt and filling strip are provided, such means comprising a plate 32 adjustably connected to the guard plate 8 by bolts or the like (not shown) which pass through slots 34 in said plate and formed to present a guiding surface 36 for engagement with the outer edge of the welt A adjacent to the point of insertion of the fastenings. Adjustment of the plate 32 relatively to the guard plate 8 permits the guiding surface 36 of the plate 32 to be aligned with the guiding surface 20 of the bracket 12 in the various adjustments of said guiding surface 20. The part 28 has its end turned laterally and extended through the passage of the bracket 12 toward the point of fastening insertion to a point adjacent to the rounded end 36 of the plate 32 so that the guiding surfaces 20 and 31 and the guiding surface 36 which acts as an extension of the guiding surface 20 operate positively to guide the welt and filling strip to the point of fastening insertion. Carried by the guide plate 32 is a finger 38 having its forward end arranged to underlie a portion of the welt A and formed to present a guiding surface 39 for guiding engagement with the outer or beaded edge of the filling strip B. The end of the finger 38 underlies the welt A and engages the filling strip B substantially at the point of insertion of the fastenings and supports the welt A at that point. The finger 38 thus acts to maintain the welt A against the lower guiding surface 10 of the guard plate 8. To the end that welts of various thicknesses may be accommodated between the guiding surface 10 of the guard plate and the finger 38, the finger is mounted for movement to and from the end of the plate 32 which engages the outer edge of the welt, as shown, by being pivoted at 40 to a block 42 which is dove-tailed slidably into the side of the guide plate 32 and is adjustably connected to said plate by the screw and slot connections 44 and normally held against the lower side of the welt A by a coiled spring 46 operating against a pin 48 seated in the finger 38. A finger piece 49 is formed on the finger 38 whereby the forward end of the finger may be lowered by the operator from the surface 10 of the guard plate 8 against the tension of the spring 46 to permit ready introduction of the welt A between the finger and the surface of the guard plate. The lower surface of the plate 32 is recessed to receive the shank portion 50 of the finger 38 thereby presenting depending portions 52 positioned at each side of the shank of the finger. Said depending

portions 52 (see Fig. 1 and broken lines Fig. 65 3) do not extend to the end of the plate 32 but stop short of the end of the guide plate sufficiently far to permit the greater portion 70 of the T-shaped end of the finger 38 to lie in the recess formed in the plate forwardly of said depending portions. The depending portions 52 of the plate 32 extend downwardly far enough to confine the shank 50 of the finger 38 between them at the extreme downward limit of movement 75 of the forward end of the finger. Such parts 52 guide the finger in its endwise adjustments and serve at all times to maintain the finger against dislocation laterally.

The plate 32 has fitted in a groove on its 80 lower side a slide 54 which has a pin 56 projecting downwardly therefrom and received within a cam slot 58 formed in a lever 60 pivoted on a pin 62 seated in said plate and passing through a slot 64 in the 85 slide 54 to permit movement of the slide relatively to the fixed pin. Said slide 54 has adjustably secured thereto at 65 a bracket 66 carrying a gage roll 68 arranged for engagement with the upper of the shoe 90 adjacent to the edge of the insole to position the shoe relatively to the fastening inserting mechanism and the guiding devices for the welt A and filling strip B. The extent of adjustment of the gage roll 68 away 95 from the fastening inserting mechanism may be regulated by the set screw 70 mounted in a bracket extending laterally from the plate 32.

The arrangement of the bead on the filling strip relatively to the margin of the shoe should be the same regardless of variation in widths of the filling strips, for which reason it is essential that the guiding device for the edge of the filling strip have a constant relation to the gage roll 68 which positions the shoe. It will be evident from the foregoing description that in the present construction the finger 38 which guides the filling strip and the gage roll 68 may be adjusted together relatively to the guard plate 8 and the fastening inserting mechanism by movement of the plate 32 relatively to the guard plate 8, such movement being permitted by the slots 34 in the plate 32. It is 105 further apparent that the notch 24 of the guiding passage formed in the bracket 12 permits adjustment of the filling strip relatively to the welt, such adjustment being effected by movement of the finger 38 endwise relatively to the plate 32 or, if it is desired to adjust simultaneously the gage roll 110 68 and the guiding surface 36 for the edge of the welt, the plate 32 may be moved relatively to the guard plate 8, thereby adjusting the filling strip B as well as the shoe 115 relatively to the fastening inserting mechanism.

the filling strip in a manner to permit adjustment of the filling strip transversely of the welt and a member presenting a guiding surface for engagement with the edge 5 of the welt adjacent to the point of attachment of the strip to the shoe and a second guiding surface for engagement with the beaded edge of the filling strip and means for adjusting said second guiding surface 10 to compensate for variations in width of the filling strip.

11. In a machine of the class described, means for attaching a filling strip having a bead projecting from its side and a welt 15 to a shoe and means for guiding the filling strip and welt and presenting them to said attaching means with the welt superposed on the shoe comprising a member formed with a guiding passage arranged rearwardly 20 of the point of attachment of the filling strip and welt to the shoe and presenting a guiding surface for engagement with the edge of the welt and having a notch in its lower wall to receive the bead of the filling strip, 25 said notch being constructed to receive the bead loosely to permit adjustment of the filling strip relatively to the guiding passage, a member presenting a guiding surface for engagement with the edge of the 30 welt adjacent to the point of attachment of the filling strip and welt to the shoe and a second guiding surface for engagement with an edge of the filling strip, and means for adjusting said second guiding surface 35 to compensate for variations in width of the filling strip.

12. In a machine of the class described, means for inserting fastenings to attach a plurality of strips of shoe stock in super- 40 posed relation on a shoe, a guard plate, devices mounted on the guard plate for guiding engagement with said strips rearwardly of the point of insertion of the fastenings, and a member carried by said guard plate 45 and constructed to present relatively adjustable surfaces for independent guiding engagement with an edge of each of said strips substantially at the point of insertion of the fastenings.

13. In a machine of the class described, means for inserting fastenings to attach a plurality of strips of shoe stock in super- 50 posed relation on a shoe, a guard plate, devices mounted on the guard plate for guid- 55 ing engagement with said strips rearwardly of the point of insertion of the fastenings, a guide plate formed to present a guiding surface for engagement with an edge of one of said strips, a member carried by 60 said guide plate and formed to present a surface for engagement with an edge of another of said strips, means carried by said guide plate for positioning the shoe, and means for securing the guide plate to 65 the guard plate for adjustment relatively

to the guard plate and the guiding devices mounted thereon.

14. In a machine of the class described, means for inserting fastenings to attach a strip having a bead projecting from its side 70 near one of its edges to a shoe, means for positioning the shoe, and means for guiding said strip into position for attachment to the shoe with its bead overhanging from the margin of the shoe and adjacent thereto, said positioning means and said guiding means being constructed and arranged for common adjustment so that upon adjustment of the guiding means to compensate for varying widths of strips, the shoe 75 positioning means is correspondingly adjusted to cause the strip to be laid on the shoe with its bead properly positioned with relation to the margin of the shoe.

15. In a machine of the class described, 80 means for attaching a strip of shoe stock to a shoe, a guide formed to present a passage to receive and guide said strip and having a guiding surface overlying said strip and extending substantially to the 85 point of attachment of the strip to the shoe, a member having a portion constructed to underlie the strip substantially at the point of attachment of the strip to the shoe, and means for yieldingly urging said last-mentioned member against the strip to maintain the strip pressed against said guiding surface but permitting said member to yield to accommodate strips of varying thicknesses. 90

16. In a machine of the class described, means for attaching a strip of shoe stock to a shoe, a guide formed to present a passage to receive and guide said strip and having a guiding surface overlying said strip and extending substantially to the 100 point of attachment of the strip to the shoe, a member having a portion constructed to underlie the strip substantially at the point of attachment of the strip to the shoe, means for yieldingly urging said last-mentioned member against the strip thereby to maintain the strip pressed against said guiding surface but permitting said member to yield to accommodate strips of varying thicknesses, and means for adjusting said last-mentioned member to vary the amount of projection of said member beneath said strip. 105

17. In a machine of the class described, 110 means for attaching a strip of shoe stock to a shoe, a guide formed to receive and guide the strip, a plate formed to present a guiding surface for engagement with the edge of the strip adjacent to the point of attachment of the strip to the shoe, a shoe positioning member spaced from said plate, a member extending beyond the guiding surface of the plate and arranged for movement between the plate and said shoe po- 115

sitioning member, and means for yieldingly urging said last-mentioned member toward said strip.

18. In a machine of the class described, means for operating on a welt and a filling strip of less width than the welt, and means for guiding the welt and filling strip to the operating means comprising a member having a welt guiding passage adapted to dispose the welt transversely in a substantially straight line and being formed to provide a recess in one of the walls of the passage to receive the filling strip in contact with the welt.
19. In a machine of the class described, means for operating on a welt and a filling strip having a bead projecting from its side, and means for guiding the welt and filling strip and presenting them to the operating means comprising a member formed with a guiding passage constructed to receive and guide the welt and filling strip in contact with each other and to arrange them transversely in substantially parallel planes and having a notch in one of its walls to receive the bead of the filling strip.
20. In a machine of the class described, mechanism formed to receive and guide a plurality of strips of shoe stock and presenting a surface for engagement with a side of one of said strips, and a member disposed for engagement with the opposite side of said strip and formed to present a guiding surface for engagement with the edge of another of said strips, said member being mounted for yielding movement away from said first-mentioned surface to accommodate strips of different thicknesses.
21. In a machine of the class described, means for attaching a plurality of strips of shoe stock of varying widths to a shoe, and means for guiding said strips in contacting relation and presenting them to the attaching means in superposed relation comprising mechanism having a surface disposed for guiding engagement with a side of one of said strips, and a member having intersecting surfaces for supporting said strip by engagement with the other side of the strip opposite from said guiding surface

and for guiding another of said strips by engagement with its edge respectively.

22. In a machine of the class described, means for attaching a plurality of strips of shoe stock of varying widths to a shoe, and means for guiding said strips in contacting relation and presenting them to the attaching means in superposed relation comprising mechanism having surfaces to guide one of said strips and a member for supporting said strip having a surface disposed in a plane transverse to the plane of the strip and intersecting one of said surfaces and constructed and arranged to guide another of said strips by engagement with its edge.

23. In a machine of the class described, means for attaching a plurality of strips of shoe stock of varying widths to a shoe, and means for guiding said strips and presenting them to the attaching means in superposed relation comprising mechanism having a surface disposed for guiding engagement with a side of one of the strips and a member movable relatively to said mechanism and disposed for engagement with the other side of the strip opposite from said guiding surface and constructed and arranged to guide another of said strips by engagement with its edge.

24. In a machine of the class described, means for attaching a plurality of strips of shoe stock of varying widths to a shoe, and means for guiding said strips and presenting them to said attaching means in superposed relation comprising a member formed to present a guiding passage arranged rearwardly of the point of attachment of the strips to the shoe and constructed to receive and guide said strips, and a member disposed for engagement with the side of one of said strips adjacent to the point of attachment of the strips to the shoe and constructed and arranged to engage the edge of another of said strips to guide the last-mentioned strip to the attaching means.

In testimony whereof we have signed our names to this specification.

FRED L. MACKENZIE.
GEORGE GODDU.
